(57) **CLAIM**

The ornamental design for surfboard carrying device, as shown and described.

DESCRIPTION

FIG. 1 is a front elevational view of a surfboard carrying device showing my new design;

FIG. 2 is a top plan view thereof;

FIG. 3 is an isometric view thereof;

FIG. 4 is a side elevational view thereof; and,

FIG. 5 is a perspective view of the surfboard carrying-device in use.

The broken lines shown in the drawings are for illustrative purposes only and form no part of the claimed design.
